UNITED STATES PATENT OFFICE.

ALBERT L. MUNSON, OF NEW YORK, N. Y.

CIGARETTE-MACHINE.

SPECIFICATION forming part of Letters Patent No. 447,968, dated March 10, 1891.

Application filed November 9, 1889. Serial No. 329,754. (No model.)

To all whom it may concern:

Be it known that I, ALBERT L. MUNSON, a citizen of the United States, residing at New York city, State of New York, have invented 5 certain new and useful Improvements in Cigarette-Machines, fully set forth in the following description and represented in the accompanying drawings.

This invention relates generally to machines for making cigarettes, and particularly to that class of such machines wherein the tobacco is formed into a proper-shaped filler and the wrapper is presented in suitable lengths to the filler and wrapped about the latter to form cigarettes.

The object of the present invention is, among other things, to provide an automatic means by which cigarettes having the characteristics of hand-work may be readily and 20 economically made; and to this end the invention consists in the novel structure and combinations of parts hereinafter fully set forth.

In the accompanying drawings, which illustrate a practical embodiment of the present improvements, Figure 1 is a plan view. Fig. 2 is a front elevation, and Fig. 2^a is a longitudinal vertical section of a portion of the filler-former, the severing device, and filler-carrier. Fig. 3 is a transverse sectional elevation taken on the line 3 3 of Fig. 1, the parts being in the position they occupy at the time the cigarette-filler is deposited on the apron of the wrapping devices. Fig. 3^a is a like view of some of the same parts, showing a portion of them in a different position. Figs. 4 and 5 are similar views of the same devices, the main shaft and cams being omitted and the parts being shown in different 35 positions. Fig. 6 is a view similar to Figs. 4 and 5, the section being taken substantially on the lines 6 6 of Figs. 1 and 2, the parts being in a slightly different position. Fig. 7, Sheet 3, is an enlarged detail elevation of the filler 40 feeder or carrier, looking from the side opposite to that shown in Figs. 3 to 6. Fig. 8 is a plan view of the wrapping devices and the operating-carriage, the immediate parts being omitted. Fig. 9 is an enlarged side elevation 45 of a portion of the structure shown in Fig. 6. Fig. 10 is a sectional elevation of the same. Fig. 11 is an enlarged front elevation of the

filler-former broken centrally to foreshorten it. Fig. 12 is a plan view of the same. Fig. 13 is an enlarged vertical central section of 55 the delivery end of the filler-former, taken on the line 13 13 of Fig. 12. Fig. 14 is an enlarged horizontal section of the same, taken on the line 14 14 of Fig. 11, only one half or one side of the filler-former being shown. 60 Fig. 15 is an enlarged cross-section of the filler-former, taken on the lines 15 15 of Figs. 11 and 12. Fig. 16 is an enlarged sectional elevation of one of the carrying-belt pulleys at the delivery end of the filler-former. Fig. 65 17 is an enlarged cross-section of the filler-former, taken on the lines 17 17 of Figs. 13 and 14. Fig. 18, Sheet 10, is a sectional elevation of the rock-arm, segment, and cam for imparting motion to the filler-carrying belts. Figs. 19 and 20 are enlarged sectional elevations of the 70 filler-severing device, the parts being shown in their changed positions. Fig. 21 is a side elevation of the same. Fig. 22 is an enlarged front elevation of the wrapper-guide and 75 pasting and carrier devices. Fig. 23 is a plan view of the same. Fig. 24 is an enlarged central vertical section of a portion of the wrapper-guide, taken on the line 24 of Fig. 23. Fig. 25 is a cross-sectional elevation on the line 25 80 25 of Fig. 24. Fig. 26 is an enlarged side elevation of the wrapper-severing device. Fig. 27 is an enlarged front elevation of the wrapper-length carrier, the side plates and platen of the wrapper device being in section. Fig. 85 28 is a cross-section on the line 28 28 of Fig. 27. Fig. 29 is a section taken on the same line and through the bar of the wrapper-carrier when in its rearmost position, illustrating also the arm for opening its gripper-fingers. 90 Fig. 30 is an enlarged cross-section taken on the line 30 of Fig. 2, the parts being broken to foreshorten them, illustrating the connections for intermittently rotating the wrapper-feed roll. Fig. 31 is a sectional elevation 95 taken on the line 31 of Fig. 30. Fig. 32 is an enlarged cross-section of the pasting device, wrapper-feed guide, and strip-holder, taken on the lines 32 32 of Figs. 1 and 2. Fig. 33 is an enlarged side elevation (the shaft being 100 in section) of a portion of the pasting device, illustrating particularly the cams for operating the paste-blade; and Fig. 34 is a sectional elevation of the same.

Before entering into a detailed description of the construction and operation of the various instrumentalities which go to make the complete organization illustrated it should be stated that such organization embraces, first, means by which the loose tobacco is formed into a properly-prepared filler of a size suited to the cigarettes to be made, hereinafter called the "filler-former;" second, means by which the prepared filler is cut off into suitable lengths and fed or carried from the filler-former to the wrapping devices, and hereinafter called the "filler feeder" or "carrier;" third, means by which an inclosing-
5 wrapper is fed forward from a roll, and also including a guide, called the "wrapper-feed;" fourth, means for applying a line of cement along an edge of the wrapper, called the "pasting device;" fifth, means for cutting
10 said inclosing-wrapper into cigarette lengths and presenting the same to the wrapping devices, called the "severing device and wrapper-carrier;" and, sixth, means by which the filler and wrapper lengths are brought together and the latter wrapped around the former, with its overlapping edges united by the line of cement to complete the formation of the cigarettes, and hereinafter called the "wrapping devices." As herein combined,
15 20 these devices co-operate automatically to prepare tobacco in the form of a cigarette-filler, feed said filler intermittently to the filler-severing device and carrier, which sever or cut off the desired length of the filler to form
25 30 a cigarette and then carry the same to the wrapping devices. While these operations are being performed the wrapper, in the form of a continuous strip, is fed or paid off intermittently from a roll and its forward end is
35 40 taken by the wrapper-carrier to the wrapping devices about simultaneous with the feeding of the filler thereto, when the wrapping devices will operate to envelop the filler by the wrapper, whose edge or edges, having
45 50 been properly cemented and overlapped, will be united and a complete cigarette will be discharged from the machine, and the operations repeated.

Referring now to the drawings, it is to be understood that these various instrumentalities are all mounted upon or carried by a supporting-table A, upon which, also, is mounted a driving-shaft H, that imparts the necessary movements to the operative parts
55 of the machine.

The filler-forming devices.—It should here be stated that any suitable devices for preparing and feeding the tobacco in proper quantities to the filler-former may be employed in connection herewith. The filler-former G (see Figs. 1, 2, and 11 to 17, inclusive) consists of an open trough formed, essentially, of three belts—a horizontally-arranged filler carrying-belt g' and two filler-carrying side belts g^4 g^5 , co-operating with the former belt and supported by a longitudinally-channelled guide F, held from the table by brackets f.

At the forward end of the guide F the trough is continued by a filler-delivery guide F', that terminates in a delivery-tube f^7 , supported from the guide F by a bracket f^6 . This tube is at one end of rectangular form and gradually merges into circular form of substantially the required diameter of the cigarette-filler. The belt g' , forming the bottom of the trough 70 in connection with the delivery-guide F', is stretched around grooved pulleys $G' G^4$, the former, at or near the forward or delivery end of the trough, being secured to a shaft g^{10} , that finds bearings in ears f^2 on the guide F, and the latter, at or near the entrance end of the 75 filler-former, being mounted in bearings provided by brackets f^5 . Of the two side belts, which form the opposite sides of the trough up to the delivery-tube f^7 , the belt g^4 is 80 stretched around grooved pulleys $G^{10} G^6$ and partially around a third pulley G^3 . The pulleys G^{10} are preferably much smaller than the others, so that the side carrying-belts may approach as near the delivery end of the 85 trough as possible, and are each mounted at said delivery end of the trough on vertical studs f^{11} , (see Fig. 16,) secured to a horizontal bracket f^{10} , that is supported by the studs f^9 of the pulleys $G^2 G^3$, and by an ear f^8 , projecting from the upper forward end of the delivery-tube f^7 , by which construction said delivery-tube is more rigidly supported. The trough is also provided with presser-rolls G^{11} G^{12} , mounted to turn loosely in brackets 90 extending from the guide. The lower portion of each of these presser-rolls extends into or between the carrying-belts and serves in conjunction with said belts in bringing the filler to proper rod shape as it is fed onward. The 95 pulleys $G^2 G^3$ are arranged so that the side carrying-belts approach nearer each other toward the delivery end of the trough, thus making the trough slightly tapering in form, and said pulleys are caused to move in unison by supplemental belts g^2 and g^3 , the latter being 100 stretched around the pulleys $G^3 G^6$ upon the inner side of the belt g^4 , and the former stretched around the pulleys $G^2 G^5$ upon the inner side of the belt g^5 , the said pulleys being properly 105 grooved to receive the two belts. The belts $g^2 g^3$ travel in contact with the sides of the channelled guide F, (see Fig. 15,) which latter is provided with guard-plates f^{12} to prevent 110 those belts as well as the carrying-belts from leaving said guide. The pulleys $G^2 G^3$ are provided on their under sides with a bevel-gear, each of which meshes with a similar gear carried by the shaft g^{10} , one upon each side of the pulley G' . Motion is communicated to the shaft g^{10} , and from thence to each 115 of the belts by a pawl and ratchet, as seen in Fig. 12. Said shaft g^{10} is extended to one side of the trough, where it passes a bearing a' , extending from the machine-table, and has 120 fast to it the ratchet-wheel G^7 , the teeth of which are engaged by the pawl g^9 , carried by a pawl-carrier g^8 , fast to a driven toothed wheel G^8 , that is mounted loosely upon said 125 130

shaft g^{10} . The toothed wheel, its pawl-carrier, and pawl are intermittently rocked from a suitably-shaped cam h^4 on the main shaft H , (see Figs. 1 and 18,) through a rock-arm G^9 , 5 pivoted at g^6 to a bracket a^2 , and having at one end a bowl g^7 for contact with said cam, and at its other end a toothed segment g^{11} , engaging with the wheel G^8 . As the cam h^4 rotates and the rock-arm thereby vibrated, 10 the toothed wheel G^8 and pawl will be correspondingly rocked to impart the necessary intermittent forward movement to the shaft g^{10} , as will be apparent. The degree of movement imparted to the carrying-belts may be 15 conveniently regulated by adjusting a stop 20, Fig. 18, so as to limit the movement of the rock-arm G^9 in one direction.

The filler-carrying devices.—The intermittent motion imparted to the filler-carrying 20 belts of the filler-former is such that at each movement a sufficient length of the prepared filler is fed through the delivery-tube f^7 to form, preferably, a single cigarette. The devices now to be described, co-operating with 25 said belts of the filler-former and the wrapping devices to be hereinafter described, receive the length of prepared filler, and, after being properly severed from the continuous filler yet under the control of the filler-former, 30 carry or present it to the wrapping devices.

The filler feeder or carrier (see Figs. 3 to 5 and 7) consists, essentially, of a pair of holders l^6 , of semi-tubular form and of a length substantially equal to that of a cigarette, that 35 are secured to the ends of a pair of arms l^4 l^5 , pivotally supported from a cross-bar L^4 , forming part of a vertically-movable rectangular frame L . This frame consists of vertical rods $L' L^2$, united at their upper ends by a cross- 40 bar L^3 and at their lower ends by the cross-bar L^4 . The frame is supported and guided in its vertical movements by brackets $l' l^2$, secured to horizontal bars $I' I^2$, forming part of the machine-frame and supported from the 45 table by legs $i' i^2$. (See Figs. 1 and 2.) The vertical rods $L' L^2$ of the frame carry springs l^8 , the tendency of which is to keep the frame in its raised or highest position. When in this position, the holders l^6 are in alignment 50 with the delivery-tube f^7 , (see Figs. 2 and 2^a), so that the prepared filler may be projected directly between said holders and at the proper time grasped thereby sufficiently to impart by their semi-tubular form a circular shape 55 to the filler-rod, aid in preserving that shape, and to carry it to the wrapping devices. Co-acting with the holders is a guard-plate l^7 of about their same length, that is supported directly beneath them by the head of a stud l^9 , 60 projecting from the arm l^5 , and by a like stud projecting from an arm l^0 , pivoted to a bracket l^{10} , that is secured to the frame L . The connection between said plate l^7 and the arm l^5 is a slotted connection permitting a considerable lateral movement between the plate 65 and the arm, so that said plate may be moved from the position shown in Figs. 3 and 7 to

that shown in Figs. 4 and 5, in which latter position it forms a bottom to the holders when in their separated position, so that the filler projected between them is held in position until the holders are moved together toward it. It will be understood that in addition to their function as a filler-carrier the holders also serve to more completely form the filler 75 while they grasp and carry it. This additional function has been found desirable in that the filler does not remain in the delivery-tube f^7 a sufficient length of time to partake of the circular shape. The movements 80 necessary to cause the holders l^6 to close around the filler and at the required time open to release the same are imparted by a cam-slot l^{15} , contained by a plate fixedly mounted on the side of the bar I' . This cam-slot is engaged 85 by a stud l^{16} , projecting from the end of a lever l^4 , that is pivotally mounted to the lower end of the frame L and at its opposite end is connected with the arm l^5 of one of the holders. The holders are connected to move in unison to 90 and from each other by links l^{13} , each connected to the opposite ends of a lever l^{12} , that rocks upon a central stud projecting from the bracket l^{10} , (see Fig. 7,) and motion is imparted to the guard-plate l^7 from the holder 95 or holders by a link l^{11} , connecting the arms l^5 and l^7 , the arrangement being such that the latter arm and the guard-plate are moved faster than the holders, so that the guard-plate in one position is beneath them before 100 they move sufficiently to grasp the filler, and in the other position is moved to one side, as in Fig. 3^a, to permit the filler to be deposited in the wrapping devices when the holders move apart for that purpose. The filler 105 having been projected between the holders and temporarily supported by the guard-plate l^7 , as in the position of these parts shown in Figs. 4 and 5, the frame L will be caused to descend through the medium of a cam h^5 (see 110 Fig. 3) acting upon the bowl l^{20} of a lever l^{18} , pivoted upon a bracket a^5 , and connected to said frame by a link l^{19} , a spring l^{21} keeping the bowl to duty. At the commencement of the descent of the frame, carrying with it the 115 holders, the guard-plate, and connecting devices, the cam-slot l^{15} being fixed, the latter will cause the lever l^4 to quickly rock and move the holders together to close upon and grasp the filler, as in Fig. 3^a. The holders will 120 remain in this position until the frame arrives at or near the limit of its downward movement, when the cam-slot, again acting upon said lever l^4 , will cause it to rock in the opposite direction, withdrawing the guard- 125 plate to one side and opening the holders, so that the filler is deposited in proper position for the action of the wrapping devices, as in Fig. 3. The frame-actuating cam h^5 will immediately permit the frame to return to its 130 raised position, as in Figs. 4, 5, and 6, ready to repeat the operation. This cam h^5 is so shaped that the frame is allowed to dwell longest in its raised position, its vertical

movements being speedy, so that the filler-carrier will not interfere with the proper and timely operation of the wrapping devices. So soon as a proper length of the filler has been projected between the holders l^6 , and while they are in alignment with the delivery-tube of the filler-former, Fig. 2^a, the filler is severed by a pair of cutters $k^1 k^2$, Figs. 19 to 21. These cutters are located immediately forward of the end of the filler-delivery tube f^7 (see Fig. 21) and between the latter and the holders l^6 , (see Fig. 22,) and are pivotally mounted on the frame K, supported by the bars I' I². One of the knives, as k^2 , is guided at its free end by a stud entering a slot k^3 in the frame. The other is guided and steadied by the said knife k^2 . They receive motion through links k^4 from a double bell-crank lever k^5 , that is mounted to a bracket k^6 , which in turn is rocked at the proper times through the movement of an arm k^7 , also pivoted to said bracket k^6 and connected to the bell-crank lever by a stud k^8 . The movement of the arm k^7 is limited in one direction by a stop-piece k^{10} , and is vibrated against the force of a spring k^9 . The requisite motion is imparted to the arm k^7 from a cam on the main shaft, which imparts a reciprocating motion to a carriage C, forming part of the wrapping devices to be hereinafter described.

The wrapper-feeder devices.—The present machine is capacitated to feed a narrow strip M of material suitable to form an envelope for a cigarette—as, for instance, paper—guide it past a pasting device R, then past a severing device O to cut the strip into wrapper lengths, and through the medium of a carrier P present the wrappers to the wrapping devices. This strip is preferably in the form of a continuous roll or web M', mounted to turn loosely in bearings provided in the brackets depending from the table, as in Figs. 2 and 22. From the roll the strip passes over a feed-roll M² under a yielding tension-roll M³, partially around a guide-bar a⁸, and then through a longitudinally-arranged guide N. The feed-roll M² is a plain disk secured to a shaft m³, that is supported in brackets a⁶ a⁷, transversely of the machine and beneath the table A. (See Figs. 30 and 31.) Intermittent rotary motion is imparted to the feed-roll from a cam h⁶ on the main shaft through a pawl m⁵ and ratchet M⁴. The ratchet is secured to the shaft m³ and the pawl is carried by a pawl-carrier m⁴, vibrating loosely on the shaft and having an operating-link m⁸, adapted to be adjustably connected with the said pawl-carrier to vary its throw. The link carries a bowl m⁹, bearing against the cam h⁶, and is held to duty by a spring m¹⁰. The ratchet is prevented from turning backward by a stop-pawl m⁷. The tension-roll M³ is hung at the end of a pair of arms m', pivoted at m² to the under side of the table. The bar a⁸ may be a fixed one, or it may turn under the action of the strip. The longitudinal guide N (see Figs. 22 to 25) is supported from the table

upon legs a⁷ and a⁹, and is channeled to receive the strip and permit the latter to move through it. The end of the guide N terminates at one side of the severing device O, and at this point is provided with a pair of spring-blades n⁸ n⁹, adapted to bear upon opposite sides of the strip, as in Fig. 24, in such a manner that its severed or forward end is bent somewhat out of the true line of travel. The severing device O (best shown in Fig. 26) is mounted on the table, and consists of a fixed jaw o', carrying a cutting-edge o² and a movable jaw o³, pivoted to the fixed jaw and carrying a cutting-edge o⁴. The jaws are mounted to give a shearing cut to the strip to sever it transversely into wrapper lengths. The requisite movement is imparted to the movable jaw o³ against the pressure of a spring o⁵ from a cam h⁷ on the main shaft, and a connecting-rod o⁶, having a bowl o⁷ operated upon by said cam. The action of the feed-roll M², it will be understood, is to intermittently feed or pay off from the web a definite length of the wrapper-strip, which, supposing the strip to be taut, as seen in Fig. 22, before this action of the feed-roll, will provide a quantity of the strip hanging loose between said feed-roll and the guide-bar a⁸, 95 no forward movement of the strip having taken place in the guide N.

It has been found in practice in using paper of the quality and weight suited to form the envelope for cigarettes that after the paper strip has been severed its forward edge will cling to the surface of the cutter, which renders it difficult to feed or carry the strip forward. To obviate this imperfect operation and to insure the forward edge of the strip being in proper position to be grasped by the wrapper-carrier, there is provided means by which this edge of the strip after each severing operation is slightly but positively withdrawn from the cutter of the severing device. Many modes of effecting this movement of the strip may suggest themselves to those skilled in the art, and in the present instance it consists of a plate n⁵, resting upon the surface of the strip and of sufficient weight when the forward end of the strip is free to depress the underlying portion into a recess, as n¹⁰, in the guide N. This, what may be termed a "withdrawing-plate," is shown as pivoted at one end to brackets n⁴, rising from the guide and having an adjustable stop n⁷ to limit the extent to which the plate will depress the strip into the recess. (See Fig. 25.) It will be understood that the plate n⁵ will also be light enough in weight to be lifted by the paper strip when it is drawn taut in the operation of feeding or carrying it forward through the severing device, and at the instant the strip is severed the forward portion thereof, not being under tension, will be readily withdrawn by the weight of the plate as it tends to seat itself in the recess n¹⁰. The accidental disturbance of the strip as it passes through the guide N

may be guarded against and sufficient friction applied to the surface of the strip to cause it to move evenly and with the proper degree of tension by any suitable means.

5 One form shown consists of a block n' , fitting between the sides of the guide and resting immediately upon the surface of the strip. It is prevented from following the strip as it is drawn or fed forward by a cross-bar n^2 , lying across its path. (See Figs. 24 and 25.) The opposite sides at its lower face are cut away, as in Fig. 25, to permit the line of paste that may have been applied to either one of the edges of the strip to pass without being 15 wiped off. The wrapper-carrier P, now to be described, operates to seize the end of the strip projecting from the end of said guide N, carry the strip bodily forward until a sufficient length to form a cigarette-wrapper has 20 passed the severing device O, when the carrier will momentarily stop to allow the severing device to sever the strip transversely, whereupon the carrier will again move to carry the severed length into position to the 25 wrapping devices, release said length, and then move to its idle position away from interference with the wrapping means.

The wrapper-carrier in the preferred embodiment consists of a reciprocating bar p' , 30 adapted to slide by its shoe p^9 in ways formed by a guide p^{10} and moved from a cam h^8 through a lever p^{12} , pivoted to a bracket-stud a^{11} , and connected to the bar by a link p^{11} . (See Figs. 1, 22, 23, and 27 to 29.) This reciprocating bar carries at its opposite end a gripper formed by a fixed finger p^2 and a movable finger p^3 , rocked open against the force of a spring p^8 . Upon the same pivot that carries the movable finger there is also pivoted a 40 tongue p^5 , that is held against a stop p^6 , carried by said finger p^3 by a spring p^7 . The operation of this tongue is such, it being understood that normally the fingers are closed, that upon the forward reciprocation of the 45 bar on its movement to seize the end of the wrapper-strip, said tongue contacting with a cam or other projection will rock the movable finger open until the two fingers are upon opposite sides of the strip, when a further movement of the bar will release the tongue and 50 permit the fingers to seize the strip between them, when the return movement of the bar will take place. In the present instance the reciprocating bar moves over a portion of the 55 wrapping devices, and to permit this a portion of the frame of the latter is cut away, as at b^{12} in Fig. 27. At one opening in this frame there is provided a cam-shaped projection b^{13} in the path of the end of the tongue p^5 , which, 60 as before described, is struck thereby and rocks it and opens the fingers of the gripper.

The opening of the fingers to release the wrapper length when in position at the wrapping devices may be accomplished in many 65 ways. There is shown a vibrating arm U, Figs. 22, 27, and 29, adapted to press against the tail of the finger p^3 and rock it open. At

the time of the action of the arm U the bar p' has come to rest, as in Fig. 22, and immediately after the finger has been rocked open 70 the bar will continue to move to its extreme rearward position, (seen in Fig. 1,) the cam h^8 being shaped to effect this operation. The vibrating arm U is pivoted to the bar I' and is vibrated from a cam h^9 on the main shaft, 75 reciprocating a rod u^2 , connected with the arm and having a bowl u^4 , bearing against said cam under the pressure of a spring u^3 .

In moving through the guide N the strip has applied to it, preferably at one edge, a narrow line of paste by the pasting device R. This device consists of a paste-fountain supported above the guide by brackets r' , secured to said guide. At the bottom of the fountain a roll r^2 is supported—a portion in the fountain and a portion out of it—by a shaft r^5 , that turns in bearings provided in the brackets r' , which shaft and roll receive continuous rotary motion from the main shaft by a pair of bevel-gears r^{13} , a transverse shaft r^{12} , and a second 85 pair of like gears $r^{10} r^{11}$, the former of which latter gears is fast to the paste-roll shaft. The opposite surfaces of the roll are borne upon by a pair of spring-plates r^3 , lying against the bottom of the fountain and regulated in pressure by screws r^4 , the action of which is to prevent the escape of the paste past the roll and fountain bottom. The roll r^2 is provided with a radial slot r^6 , extending its length, in which is seated a paste-applying blade r^7 , the said 90 roll and blade extending longitudinally with the strip. The paste-roll rotates just above the upper surface of the wrapper-strip, passing beneath it, as seen in Fig. 32, so that said roll does not meet the strip at any time. The 100 paste-applying blade normally lies with its outer edge flush with the roll-surface, or, as in the preferred construction, slightly below that surface, so that a film of paste upon the edge of the blade will escape the clearing action of the fountain-bottom or of one of the plates r^3 , and at the proper time the pasting-blade will be moved outward sufficient to apply a line of paste to the edge of the strip directly beneath it. This action of the blade is 105 effected by a cam r^{15} , Figs. 33 and 34, duplicated at both ends of the roll and secured to the sides of the fountain. The blade carries a finger r^8 , projecting from opposite ends of the roll, which fingers each carry a pin r^9 , 120 extending through an opening in the roll-shaft and contacting with the cam r^{15} , so that in the rotation of the roll the blade will be moved outward. The return movement of the blade is effected by a second cam r^{14} , also 125 duplicated on opposite ends of the roll in position to contact with each of the fingers r^8 after the blade has applied its line of paste to the strip. It should be stated that at the 130 time the blade applies its line of paste the strip is stationary, its intermittent movement being had after the blade has performed its duty, so that the paste is applied in an unbroken line. As the action of the pasting-

blade, which in effect is a lateral wiping one, in applying its paste to the strip may tend to disturb the position of the strip in its guide there is provided a temporary holding-finger 5 to obviate such disturbance. A finger r^{16} , Figs. 1, 23, and 32, is pivoted at r^{17} to the side of the guide N , and held pressed upon a portion of the strip in line directly opposed to the contact of the blade with the strip by a 10 spring r^{18} . Just before the movement of the strip the pressure of the finger is relieved by the contact of an adjustable stud r^{22} of a rod r^{19} , that is acted upon by a cam h^{10} , carried by the main shaft. The rod r^{19} is pivoted to 15 a bracket a^{13} , and its bowl r^{20} is held to duty upon the cam by a spring r^{21} .

The wrapping devices.—All of the various instrumentalities forming the complete organization have been described with the exception of the devices which act to bring the prepared cigarette-fillers and the wrapper lengths together and envelop the former by the latter and discharge the completed cigarettes. The wrapping devices, Figs. 2 to 6 and 25 8 to 10, consist, essentially, of a belt or apron D , upon which the cigarette filler and wrapper are deposited, and a traveling blade c^{11} , which imparts a rolling or wrapping action to the apron. The apron rests upon a platen 30 E , and is confined between a pair of side plates B' , and the blade c^{11} is mounted on a reciprocating carriage C , that is guided by blocks c' , moving in slotted guideways b' in the side plates. The blocks c' are secured to 35 the carriage by side plates c^2 . The forward end of the apron is fixedly attached to the platen by a bar b^3 , confining that end of the apron in a groove in the platen, this end of the platen being inclined to allow the cigarettes to be conveniently discharged, while the 40 remaining portion is level. The opposite end of the apron passes beneath a cross-bar b^4 , and is held by a take-up or let-off rod d , that is mounted in brackets d' and provided at 45 one end with a tooth-wheel d^2 , engaged by a stop-pawl d^3 . The purpose of thus adjustably securing the end of the apron is to permit the size of the apron-fold d^4 , hereinafter described, to be regulated so that cigarettes 50 of different sizes may be properly rolled thereby, to regulate also the tight or loose rolling of the cigarette, and, further, to supply fresh portions of the apron when it becomes worn. The traveling blade c^{11} lies beneath the apron, and is carried by a bar c^3 , adapted to rock in bearings formed by the guide-blocks c' of the carriage, and at one end said rock-bar c^3 projects to the outer side of the carriage, and is connected by a link c^4 55 to a vertically-reciprocating bar c^6 , mounted to travel with the carriage and connected thereto by a stud c^8 , extending through a guide-slot c^7 in the bar, the said stud projecting from a bracket c^9 , rising from the carriage, Figs. 6, 9, and 10. The lower end of the bar c^6 has a bowl c^{10} , that engages with the cam-groove of a plate-cam B^3 , fixed to one

of the side plates B' of the wrapping devices. The construction of the parts is such that upon the movement of the carriage C from the position shown in Figs. 3 and 9 the cam B^3 will first permit the traveling blade to move until it brings the fold of the apron over the filler, when said cam will cause it to suddenly rock from its inclined position to the vertical position indicated by dotted lines, Fig. 4, so that the filler is firmly confined in the fold d^4 of the apron. The carriage continuing to move, with the blades in this last-named position, will cause the apron to roll around the filler and impart a rotary motion to the filler preparatory to its meeting the wrapper length, which has been properly laid upon the apron by the wrapper-carrier P . Immediately prior to the bite of the apron around the end of the blade reaching the edge of the wrapper length the said cam will cause the blade to rock upward slightly sufficient to loosen the hold of the apron-fold d^4 upon the filler, and as the filler arrives over the edge of the wrapper length the cam will again bring the blade to its vertical position, as in Fig. 5, confining the wrapper length and filler within the apron-fold d^4 . The carriage C still continuing its forward movement will impart the rolling motion to the wrapper length, (as well as to the filler,) so that the former is brought entirely around the filler with its edges overlapping one another, which by reason of the line of paste applied to the wrapper length will become united, whereupon the said cam will again cause the blade to rock to its inclined position, entirely freeing the now completed cigarette and permitting it to be discharged over the inclined end of the platen just as the carriage reaches the limit of its forward movement. Motion is imparted to the carriage C , and thence to the blade c^{11} , from a cam h^2 on the main shaft (see Fig. 3) through a rod c^{21} , having a bowl h^3 , engaging with the cam, a bell-crank lever c^{20} , and a forked connecting-rod c^{19} , which in turn is connected with the carriage.

To prepare the apron for its rolling action after each cigarette has been formed, so that it lies perfectly flat upon the platen and free from wrinkles or creases, and also to insure the formation of the necessary fold d^4 in the apron behind the traveling blade as the latter begins its forward movement, there is provided a tongue c^{13} , arranged and operated in such manner that immediately upon the discharge of the finished cigarette from the apron it drops with its edge upon the apron, and as the carriage C moves back to its normal position it follows immediately behind the blade, smoothing the apron down upon the platen in its movement until the blade and the carriage reach their normal position to permit the described operations to be performed as the carriage again moves forward. This tongue c^{13} is held to a pivoted rod c^{12} , mounted to the rear of the carriage C , a spring c^{15} , that is carried by the tongue, (a weight

would serve the same purpose,) bearing against a plate c^{14} , secured to the carriage, tending to elevate the forward edge of the tongue.

5 In order to automatically operate the tongue near its forward edge it carries a transverse guide-bar c^{17} , adapted in the raised or idle position of the tongue to rest and slide upon the surface of each of the side plates B' , as 10 in Fig. 8, and in its lower or active position to slide within the guide-slots b' . At the limits of the movement of the guide-bar in both directions both of the side plates B' are slotted, as $b^7 b^8$, the former to permit the ends 15 of the guide-bar to pass downward into the guide-slots b' , and the latter to permit them to pass up onto the surface of the side plates. In the extreme forward movement of the carriage C and of the tongue one end of the 20 guide-bar c^{17} contacts with a deflector b^6 , pivotally mounted on an upright b^5 and held in position by a spring b^9 , the effect of which deflector is to direct the guide-bar into the slot b^7 , and, by reason of the latter's inclined 25 position, on the return movement of the carriage and the tongue will direct the tongue down so that its edge bears against the apron, in which position it will travel until the guide-bar underlies the slots b^8 , when the spring 30 will cause it to rise to its idle or normal position.

In order to insure the formation of the apron-fold d^4 , the parts are constructed to impart an additional or further movement to the tongue c^{13} . To this end the rectangular frame L , as it reaches the limit of its downward movement in the act of depositing the filler carried by the holders l^6 upon the apron of the wrapping devices, will contact with the 35 tongue and further depress it, so that its end is carried under the traveling blade c^{11} sufficient to form the apron-fold d^4 , as seen in Fig. 3. Instead of contacting directly with the tongue, a spring-leaf c^{16} is interposed, carried by the tongue, so that the tongue may 40 yield slightly and the force of the contact of the frame lessened. So soon as the frame L begins to move to return to its upper position 45 the tongue will immediately rise to its idle position, (shown in Fig. 4,) ready for the forward movement of the carriage C .

As the wrapper-carrier P deposits the wrapper length in position upon the apron and then moves back to its normal position 55 there is danger of the said wrapper length being displaced by currents of air due to the rapid movements of the parts. To avoid this, there is provided a temporary retainer adapted to rest upon the wrapper length and hold 60 it in position until or just before the filler is brought up to it by the traveling blade c^{11} . This wrapper-retainer (see Figs. 2 to 6) preferably consists of one or more pins s^6 , two being shown, weighted slightly and supported 65 loosely by a bar s^5 at the lower end of a vertically-movable rod s' , which slides in ears s , formed on a bracket S , that is secured to and

carried by the rectangular frame L . The rod s' carries a spring s^3 , the tendency of which is to hold it in its raised position with respect to 70 the frame. The rod is also provided with a collar s^4 , adjustably secured thereto and engaging the sides of the bracket S to prevent the rod from turning and thus hold the position of the retaining-pins s^6 . On the downward 75 movement of the frame L the rod s' moves with it until its retainer-pins s^6 rest by their own weight upon the wrapper length, when upon a slightly further movement of the frame and rod the collar s^4 on the latter will 80 have passed a dog t^3 , that is mounted at the end of a lever T , pivoted to the bar I' . This dog is pivoted to the lever and weighted, so that on the downward movement of the rod s' its collar vibrates it to one side, and when 85 below it the dog will extend over the collar and prevent it and the rod s' from rising, a stop-pin t^5 limiting the movement of the dog in one direction. Upon the return movement of the frame L it will carry with it the 90 bracket S , thus compressing the spring s^3 of the rod s' , so that at the proper time sufficient power will have been stored up to return the rod and its retainer-pins to their 95 normal or raised position. The latter movement of the rod and its retainer-pins will occur when the dog t^3 releases its hold upon the collar s^4 of the rod, and to effect this at the proper time a cam or contact plate c^{18} , carried by the carriage C , is made the means by 100 which this is accomplished. This cam is secured to the upper end of the bracket c^9 , (see Figs. 2, 6, 9, and 10,) and in the forward movement of the carriage bears against the end of the lever T and rocks it against the pressure 105 of the spring t' , (which tends to keep its stop-pin t^2 against the cam-plate c^{18}), so as to move the dog t^3 from the collar, freeing it, and allowing the rod to return to its normal position. The movement of the carriage C also 110 vibrates the operating-arm k^7 of the filler-severing device heretofore described, and shown by Figs. 1 and 19 to 21. The end of the arm is provided with a pivoted finger k^{11} , having a stop k^{13} borne against a projection k^{14} 115 of the arm by a spring k^{12} . Thus the finger is rigid with the arm when borne against in one direction and yielding when borne against in the opposite direction. In the forward movement of the carriage it will contact with 120 the finger k^{11} idly; but on the return of the carriage in contacting therewith in the direction of the arrow, Fig. 19, will rock its arm k^7 and operate the severing device, as in Fig. 20, which arm after each rocking movement 125 will be returned to its normal position by the force of its spring k^9 , at the same time opening its cutters, ready to sever the filler that is projected past them into the holders of the 130 filler-carrier.

Motion may be imparted to the main shaft H and through it to the various instrumentalities described in any convenient manner. There is shown a supplemental shaft H' ,

mounted in bearings provided on the table of the machine, and having a pinion W gearing with a wheel fast to the shaft H. The said supplemental shaft is also provided with fast 5 and loose driving belt-pulleys V V' and a balance or hand wheel X.

From the foregoing description it is deemed unnecessary to separately describe the operations of the various parts of the improved 10 machine, as those not specifically mentioned will be obvious to those skilled in the art of making cigarettes. It is to be remarked, however, that the operations of the various devices are so timed with respect to each other 15 that they will operate to advance the filler and the wrapper to the wrapping-apron, the latter being in position to receive said filler and wrapper, and while the wrapping operation is being performed the filler and wrapper 20 for the succeeding cigarette is prepared and ready to be advanced so soon as the wrapping-apron has completed its operation, thus rapidly making complete cigarettes in 25 succession, which, from the nature of the apparatus, mode of manipulating the tobacco for the filler, and the manner of inclosing it with the wrapper, will equal hand-made cigarettes.

It is to be remarked in conclusion that the 30 invention is not deemed as limited to the employment of all of the various instrumentalities in combination in a machine of the character described, as it will be obvious that many of the parts may be utilized effectively 35 in other cigarette-making machines. So, too, changes and omissions may be made in the machine—as, for instance, the positive paying out of the wrapper-strip from its roll may be entirely omitted, the wrapper-carrier performing the function of drawing the strip 40 from the roll. It has been demonstrated, however, that owing to the frail character of the paper necessarily employed this paying out of the strip independent of the feeding 45 action of the wrapper-carrier is more desirable.

The mode of operating the paste-blade may be departed from. Instead of using two cams, as shown, a single box-cam would perform the 50 same function, or one of the cams and a spring for returning the blade.

Without, then, limiting the invention to the specific details of construction shown and described, what is claimed is—

55 1. The combination, in a cigarette-machine, with the devices for forming the filler-rod and devices for wrapping the wrapper around the filler-rod, of a filler-rod carrier consisting of a pair of semi-tubular filler-grasping holders 60 interposed between the said devices, means, substantially as described, for moving the holders to grasp and release the filler-rod, and means for operating each of said devices and the filler-carrier, substantially as described.

65 2. The combination, with a filler-rod former, a severing device therefor, a wrapper-carrier, and a wrapper-apron, of a filler-rod carrier

70 consisting of a pair of semi-tubular grasping-holders adapted to grasp and carry the severed filler-rod to the wrapper-apron, means, substantially as described, for moving the holders to grasp and release the filler-rods, and means for causing the wrapper-apron to wrap the wrapper around the filler-rod, substantially as described. 75

3. The combination, in a cigarette-machine, of a filler-rod former, a severing device for the filler-rod, a movable filler-rod carrier consisting of a pair of grasping-holders adapted in one position to be in axial alignment with the former to receive the filler-rod therefrom and to grasp the same, the wrapping devices, and means for operating the filler-rod former, carrier, and wrapping devices, substantially as described. 80

4. In a cigarette-machine, the combination, with intermittently-moving belts, a compressor, as the roll G¹², and a delivery-tube for forming the filler, of a filler-severing device, a filler-carrier, an intermittently-moving wrapper-carrier, a wrapping-apron, and means for causing the wrapping-apron to wrap the wrapper around the filler, substantially as described. 85

5. In a cigarette-machine, the combination, 90 with the intermittently-moving belts, presser-roll, and delivery-tube for forming the filler, and a filler-severing device, of a vertically-movable filler-carrier consisting of a pair of grasping-holders, an intermittently-moving wrapper-carrier, a wrapping-apron, and means for causing the wrapping-apron to wrap the wrapper around the filler, substantially as described. 95

6. In a cigarette-machine, the combination, 100 with the intermittently-moving belts, presser-roll, and delivery-tube for forming the filler, and a filler-severing device, of a pair of separable and filler-grasping holders forming the filler-carrier, an intermittently-moving wrapper-carrier, a wrapping-apron, and means for causing the wrapper to wrap the wrapper around the filler, substantially as described. 105

7. In a cigarette-machine, the combination, 110 with the intermittently-moving belts, presser-roll, and delivery-tube for forming the filler, and a filler-severing device, of a pair of separable holders forming the filler-carrier, a guard-plate therefor, an intermittently-moving wrapper-carrier, a wrapping-apron, and means for causing the wrapping-apron to wrap the wrapper around the filler, substantially as described. 115

8. In a cigarette-machine, the combination, 120 with a filler-former, a filler-severing device, and a filler-carrier consisting of a pair of filler-grasping holders, of a guide for the wrapper-strip, a strip-severing device, a wrapper-length carrier, a wrapping-apron, and means for causing the wrapping-apron to wrap the wrapper around the filler, substantially as described. 125

9. In a cigarette-machine, the combination, 130 with a filler-former, a filler-severing device,

- and a filler-carrier consisting of a pair of filler-grasping holders, of an intermittently-operating wrapper-feeder, a strip-severing device, an intermittently-moving wrapper-length carrier, a wrapping-apron, and means for causing the wrapper-apron to wrap the wrapper around the filler, substantially as described.
- 5 10. In a cigarette-machine, the combination, with a filler-former, a filler-severing device, and a filler-carrier consisting of a pair of filler-grasping holders, of an intermittent wrapper-strip feeder, a strip-severing device, a reciprocating wrapper-carrier for carrying the wrapper-lengths, a wrapping-apron, and means for causing the wrapping-apron to wrap the wrapper around the filler, substantially as described.
- 10 15 11. In a cigarette-machine, the combination of a filler-former, a filler-severing device, a filler-carrier consisting of a pair of filler-grasping holders, a wrapper-carrier, a wrapping-apron, and a traveling blade for rolling the apron around the filler and wrapper, substantially as described.
- 20 25 30 35 12. In a cigarette-machine, the combination of the intermittently-moving belts, presser-roll, and delivery-tube for forming the filler, a filler-severing device, a filler-carrier consisting of a pair of filler-grasping holders, an intermittently-moving wrapper-carrier, a wrapping-apron, and a traveling blade for rolling the apron around the filler and wrapper, substantially as described.
- 40 45 50 55 13. In a cigarette-machine, the combination of the intermittently-moving belts, presser-roll, and delivery-tube for forming the filler, a filler-severing device, a filler-carrier consisting of a pair of filler-grasping holders, a guide for the wrapper-strip, a severing device therefor, a reciprocating wrapper-length carrier, a wrapping-apron, and a traveling blade for rolling the filler and wrapper, substantially as described.
- 60 65 70 75 14. In a cigarette-machine, the combination of means for forming a filler-rod, consisting of a channeled guide, three carrying-belts and pulleys therefor, means for compressing the filler downwardly between the belts, a delivery-tube, the latter being fixed with respect to the belts, and means for carrying and wrapping the formed rod, substantially as set forth.
- 80 85 89c 90 95 100 105 110 115 120 125 130 135 140 145 150 155 160 165 170 175 180 185 190 195 199 200 205 210 215 220 225 230 235 240 245 250 255 260 265 270 275 280 285 290 295 299 300 305 310 315 320 325 330 335 340 345 350 355 360 365 370 375 380 385 390 395 399 400 405 410 415 420 425 430 435 440 445 450 455 460 465 470 475 480 485 490 495 499 500 505 510 515 520 525 530 535 540 545 550 555 560 565 570 575 580 585 590 595 599 600 605 610 615 620 625 630 635 640 645 650 655 660 665 670 675 680 685 690 695 699 700 705 710 715 720 725 730 735 740 745 750 755 760 765 770 775 780 785 790 795 799 800 805 810 815 820 825 830 835 840 845 850 855 860 865 870 875 880 885 890 895 899 900 905 910 915 920 925 930 935 939
- for the filler, consisting of a pair of cutters, a lever and connections with both of the cutters, and an operating-arm, substantially as described.
17. In a cigarette-machine, the combination, with the filler-former and wrapping devices and means for conducting the formed filler to the wrapping devices, of a severing device for the filler, consisting of a pair of pivoted cutters, a double bell-crank lever and connections with both of the cutters, and an operating-arm, substantially as described.
18. In a cigarette-machine, the combination, with the wrapping devices, of a vertically-reciprocating frame, a pair of separable filler carrying and grasping holders, each of semi-tubular form, carried by said frame, substantially as described.
19. In a cigarette-machine, the combination, with the wrapping devices, of a vertically-reciprocating frame, a pair of filler-carrying holders, each of semi-tubular form, pivoted to said frame, and a cam and connections for moving the holders to and from each other, substantially as described.
20. In a cigarette-machine, the combination, with the wrapping devices, of a vertically-reciprocating frame, a pair of separable filler-carrying holders carried by said frame, a guard-plate for the holders, and means for operating the holders and guard-plate, substantially as described.
21. In a cigarette-machine, the combination, with the wrapping devices, of a vertically-reciprocating frame, a pair of filler-carrying holders pivoted to said frame, a guard-plate for the holders, and a cam and connections for vibrating the holders and moving said guard-plate, substantially as described.
22. In a cigarette-machine, the combination, with the wrapping devices, of a vertically-reciprocating frame, a pair of filler-carrying holders pivoted to said frame, a guard-plate mounted beneath said holders, a fixed cam, a lever carried by the frame connected with the holders and engaging said cam, and connections for operating the guard-plate, substantially as described.
23. The combination, with a guide for the wrapper-strip and a severing device therefor, of means, substantially as described, for withdrawing the forward edge of the strip from the blade of the severing device, substantially as described.
24. The combination, with a guide for the wrapper-strip, a severing device therefor, and a wrapper-carrier, of means, substantially as described, for withdrawing the forward edge of the strip from the blade of the severing device, substantially as described.
25. The combination, with a guide for the wrapper-strip, having a transverse recess therein, and a severing device for the strip, of a plate adapted to bear upon the strip over said recess in the guide for withdrawing the forward edge of the strip from the severing device, substantially as described.

26. The combination, with a guide for the wrapper-strip, having a transverse recess therein, and a severing device for the strip, of a pivotally-mounted plate, its edge adapted to bear upon the strip over said recess in the guide for withdrawing the forward edge of the strip from the severing device, substantially as described.

27. The combination, with a guide for the wrapper-strip and a severing device therefor, of a withdrawer for withdrawing the forward edge of the strip from the blade, and a reciprocating wrapper-carrier for grasping the end of the strip and carrying it forward, substantially as described.

28. The combination, with a guide for the wrapper-strip, having a transverse recess therein, and severing device therefor, of a plate adapted to bear upon the strip above said recess in the guide for withdrawing the forward edge of the strip from the severing device, and a wrapper-carrier for grasping the end of the strip and carrying it forward, substantially as described.

29. The combination of a guide for the wrapper-strip, a severing device therefor, spring-plates mounted to bear upon opposite sides of the wrapper-strip, and a wrapper-carrier for grasping the end and carrying it forward, substantially as described.

30. The combination of a guide for the wrapper-strip, a severing device therefor, spring-plates mounted to bear upon opposite sides of the strip, means for withdrawing the forward edge of the strip from the severing device, and a wrapper-carrier for grasping the end of the strip and carrying it forward, substantially as described.

31. The combination of a support for a wrapper-strip roll, a feed-roll therefor, a guide for the strip, a strip-severing device, and an intermittently-operated wrapper-carrier, which grasps the end of the strip and conveys it forward independent of the feed movement of the feed-roll before the said strip is severed to form the wrapper, substantially as described.

32. The combination of a support for a wrapper-strip roll, an intermittently-rotated feed-roll therefor, adapted to pay off a definite length of strip, a guide for the strip, a severing device, and a reciprocating wrapper-carrier, which grasps the end of the strip and conveys it forward before the said strip is severed to form the wrapper, substantially as described.

33. The combination, with a guide for a wrapper-strip, of a pasting device consisting of a paste-fountain, a rotating roll, and a radially-reciprocating paste-blade, substantially as described.

34. The combination, with a guide for a wrapper-strip, of a paste-fountain, a roll, and an intermittently-operating paste-blade, extending longitudinally with the strip, substantially as described.

35. The combination, with a guide for a

wrapper-strip, of a paste-fountain, a roll, an intermittently-operating paste-blade extending longitudinally with the strip, and an intermittently-operated wrapper-carrier, substantially as described.

36. The combination, with a guide for a wrapper-strip, of a rotating roll carrying a radially-reciprocating paste-blade and an intermittently-operated wrapper-carrier, substantially as described.

37. The combination, with a guide for a wrapper-strip, of a pasting device consisting of a fountain, a roll rotating partially within the fountain and carrying a radially-reciprocating paste-blade, and a pair of spring-pressed plates bearing against the roll to prevent the escape of paste, substantially as described.

38. The combination, with a guide for a wrapper-strip, of a paste-fountain, a paste-roll, a radially-reciprocating paste-blade carried thereby, and a cam for projecting the blade, substantially as described.

39. The combination, with a stationary guide for a wrapper-strip, and a pasting device for applying a line of paste to the strip, of a holding-finger adapted to hold the strip against disturbance during the pasting operation, substantially as described.

40. The combination, with a stationary guide for a wrapper-strip and a pasting device moving laterally against the surface of the strip, of a holding-finger adapted to hold the strip against the lateral movement of the pasting device, substantially as described.

41. The combination, with a guide for a continuous wrapper-strip and a paste-blade applying lines of paste intermittently along one edge of the continuous strip, of an intermittently-operated holding-finger for the strip, substantially as described.

42. In a cigarette-machine, the combination of a wrapper-apron, a traveling blade for imparting the rolling motion to said apron, and a cam for controlling the position of the edge of the blade with respect to the horizontal surface of the apron, substantially as described.

43. In a cigarette-machine, the combination of a platen, a wrapping-apron thereon, a traveling blade for imparting the rolling motion to said apron, and a cam for controlling the position of the edge of the blade with respect to the horizontal surface of the apron, substantially as described.

44. In a cigarette-machine, the combination of a wrapping-apron, a reciprocating carriage, a blade pivoted to said carriage for imparting the rolling motion to said apron, and a cam for controlling the position of said blade, substantially as described.

45. In a cigarette-machine, the combination, with a wrapping-apron and a traveling blade for imparting the rolling motion to said apron, and a cam for controlling the position of the edge of the blade, of a wrapper-carrier reciprocating transversely across the apron, substantially as described.

46. In a cigarette-machine, the combination, with the side guides and platen of the wrapping devices, of a wrapping-apron located between said side guides, a traveling blade for imparting the rolling motion to said apron, an adjusting-rod to which one end of the apron is attached, and a toothed wheel and holding-pawl for the rod, substantially as described. 5
- 10 47. In a cigarette-machine, the combination of a wrapping-apron, a traveling blade for imparting the rolling action to said apron, and a vibrating and traveling tongue carried with the blade for forming the apron-fold to one side of the blade, substantially as described. 15
- 15 48. In a cigarette-machine, the combination of a wrapping-apron, a traveling blade, a vibrating tongue, and a deflector for rocking the tongue into operative position, substantially as described. 20
- 20 49. In a cigarette-machine, the combination of a wrapping-apron, a traveling blade, side guides for supporting and guiding said blade, a vibrating tongue traveling with the blade, 25 and a deflector for rocking the tongue into operative position, substantially as described. 25
- 30 50. In a cigarette-machine, the combination of a wrapping-apron, a traveling blade, a vibrating and traveling tongue, a deflector for 30 said tongue to cause it to move along in contact with the apron in one direction, and means for imparting an additional movement to the tongue to form the apron-fold to one side of the blade, substantially as described. 35
- 35 51. In a cigarette-machine, the combination of a wrapping-apron, a reciprocating carriage, 40 a blade pivotally mounted thereon, a cam, and connections mounted on the carriage for rocking the blade, substantially as described. 45
52. In a cigarette-machine, the combination, with a filler-carrier and a wrapper-carrier, of a wrapping-apron, a traveling blade, and a cam for controlling the position of the edge of the blade with respect to the rolling surface of the apron, substantially as described. 45
53. In a cigarette-machine, the combination, with the wrapping devices and a wrapper-carrier, of a retainer for temporarily holding the inclosing-wrapper and mounted above the wrapping devices, substantially as described. 50
54. In a cigarette-machine, the combination, with the wrapping devices and a wrapper-carrier, of a temporary retainer for the inclosing-wrapper, a dog for holding the retainer in action, and a cam for tripping the 55 dog to allow the retainer to return to its idle position, substantially as described.
55. In a cigarette-machine, the combination, with the wrapping devices, a filler-carrier, and a wrapper-carrier, of a reciprocating frame, a temporary retainer for the inclosing-wrapper carried thereby, a dog for holding the retainer in action independent of the frame, and a cam for tripping the dog, substantially as described. 60 65

Signed in the presence of two subscribing witnesses this 5th day of November, 1889.

ALBERT L. MUNSON.
